BUMPER

Villor P. Williams, Baltimore, Md., assignor to
Estelle Williams Gomborov, Baltimore, Md.

Application January 8, 1935, Serial No. 929

22 Claims. (Cl. 293—55)

This invention relates to vehicle bumpers and is an improvement over the bumper construction shown in my prior Patent No. 1,957,515, granted May 8, 1934 as well as a continuation in part 5 of my copending application Serial No. 724,402 filed May 7, 1934. This invention is furthermore an improvement over the subject matter disclosed in my other copending application Serial No. 755,821 filed Dec. 3, 1934.

Both in my prior patent and in my first mentioned application I have shown a bumper comprising a main or impact receiving bar and a back bar provided with spring arms that slidably engage the main bar. In my prior patent the 15 main bar was provided with means acting to guide the spring arm in its sliding movement relative to the main bar. In my first mentioned copending application there was provided in addition to the guiding means, resilient means 20 which functioned to produce a frictional resistance to the sliding and vibratory movements of the spring arms.

The invention set forth in my latter copending application relates to the employment of various 25 forms of resilient means designed not only to provide the necessary frictional resistance to the sliding and vibratory movements of the spring arms but also to add a supporting strength to the shock absorbing characteristics of the spring 30 arms. In each of these copending applications the slideable ends of the spring arms frictionally engage flat plane surfaces on the main bar that are substantially parallel to the plane of the main bar, the resilient means in each case acting 35 normal to the spring arms and to the surfaces on which the same slide.

It is accordingly the main object of this invention to employ in addition to the static frictional 40 resistance set up by the above mentioned resilient means an additional resistance imparted to the ends of said spring arms directed along the plane of said spring arms which resistance may be produced either by a cam surface over which the ends of the spring arms slide on by the 45 provision of a resilient medium adapted to be directly engaged and compressed by said spring arm ends.

Another object of this invention resides in the 50 functioning of the spring arm as a reinforcing means for the main bar as the same is actuated by impacts.

The above specified objects along with those 55 set forth in my latter copending application as well as other objects of this invention, will be come apparent as the description thereof given

hereunder proceeds, reference being now had to the accompanying drawings in which like parts have the same reference characters and wherein:—

Fig. 1 is a plan view of a bumper construction 5 showing double spring arms connected to the main bar by a single housing.

Fig. 2 is a partial central rear elevational view of the bumper showing the housing.

Fig. 3 is a plan view of a modified form of 10 bumper construction wherein each spring arm is connected to the main bar by an individual housing.

Fig. 4 is a plan view of a modified form of bumper construction wherein the spring arms are 15 carried by the main bar and each connected by an individual housing to the vehicle frame.

Fig. 5 is a partial sectional view taken on line 5—5, Fig. 2, in the direction of the arrows.

Fig. 6 is a view similar to Fig. 5 showing a modified construction employing helical springs.

Fig. 7 is a view similar to Fig. 5 showing a modification thereof.

Figs. 8, 9, 10, 11 and 12 illustrate modified forms of spring arms and connections therefor; 25 Fig. 10 being a detail sectional view of Fig. 9, and Fig. 12 being a sectional view taken on line 12—12, Fig. 11.

Fig. 13 is a view similar to Fig. 5 showing a 30 rubber spring and cam construction.

Fig. 14 shows in an individual spring arm connection, a rubber spring assembly.

Fig. 15 shows in a double spring arm connection a volute and rubber spring arrangement.

Fig. 16 is a sectional view taken on line 16—16, 35 Fig. 15.

Fig. 17 shows a modification of the connection shown in Fig. 15.

Fig. 18 shows in a double spring arm connection, an eccentric mounting for the spring arm ends. 40

Figs. 19, 20, 21, 22, 23 and 24 show various embodiments of a still further modified manner of mounting the spring arm ends by a pin and slot connection to a cam member; Fig. 22, being a sectional view taken on line 22—22, Fig. 21, and 45 Fig. 24 being a sectional view taken on line 24—24, Fig. 23.

Figs. 25, 26 and 27, respectively, show diagrammatically, the force distribution on the bumper elements in the normal relationship of 50 parts and under an impact received thereby.

In Fig. 1 there is shown a complete bumper embodying my invention which bumper comprises an impact or main bar 1 and back bars 2, the outer ends thereof being connected to the main 55

bar 1 in any suitable manner as at 3. The back bars 2 are formed with oppositely disposed spring arms 4, the ends of which are disposed within a housing 5 for slidable engagement with a surface on said main bar arranged within said housing all in a manner to be hereinafter described.

The form of bumper shown in Fig. 3 differs from that of Fig. 1 only in that each spring arm 4 is provided with an individual housing 6. Both the bumpers of Figs. 1 and 2 are mounted on the frame horns 7 and are connected thereto in any suitable manner as by the bolts 8.

In Fig. 4, the main bar 1a has the ends thereof secured to the frame horns 7, which ends also carry the housings 10. In this form of construction the spring arms 4a are carried by the main bar 1a, being secured thereto at one end as at 11, the other end thereof being disposed within the housing 10 for sliding engagement with a surface arranged therein.

The three forms of bumpers illustrated in Figs. 1, 3 and 4 are merely illustrative of conventional forms of bumper design, the herein described invention residing solely in the connections contained in the housings 5, 6 and 10 which include means for not only retaining the spring arms 4 and 4a in frictional sliding engagement on suitable surfaces arranged within the housings but also in the provision of additional means within the housing for imposing a resistance to the end-wise movement of said spring arms. In my co-pending application Serial No. 755,821 filed December 3, 1934, there has been disclosed a variety of resilient units which act in a direction normal to the spring arms to produce a frictional resistance to the sliding movement of the same. It is accordingly desired understood, that I contemplate the use of any one of the resilient units described in said copending case in the herein to be described housing connections for use as the above indicated means therein for retaining the spring arms 4 and 4a in frictional sliding engagement with the surface arranged within said housing.

The description of the various forms of housing connections embodying the present invention will now be set forth.

The housing connection in Fig. 5 comprises a substantially four sided tubular housing 15 provided with open ends 16. Arranged centrally within the housing 15 is a cam block 17 provided with a bore 18 through which the bolt 19 extends to attach the housing 15 to the main bar 1. The cam block 17 acts as a spacer element to prevent buckling of the walls of the housing by the clamping pressure exerted to the nut 20 on the bolt 19. Arranged adjacent the wall 21 of the housing that contacts the inner side of the main bar 1 is a wear plate 23 formed of any suitable material and which is clamped in position by the cam block 17 and any other suitable means not shown.

Extending within the housing 15 are the spring arms 4 the end portions thereof being adapted to slidably engage the wear plate 23. As the connections on each side of the housing are identical, only one side thereof shown in detail will be described. This will be done with all other double spring arm connections to be described hereinafter.

To retain the slidable end portion 4b of the spring arm in frictional engagement with the wear plate 23 there is provided a laminated spring 24 held against longitudinal bodily movement with respect to the housing 15 by the bosses 25 thereon that cooperate with the slots 26 formed

in the sides of the laminated spring. A bearing element or button 27 is carried by the spring 24 for bearing engagement with the adjacent side of the spring arm end 4b.

The cam block 17 is provided with two cam surfaces 30 of a concave curvature that extends from a point substantially adjacent the end of the slidable spring arm portion 4b and the front housing wall 21, to the rear wall 27 of the housing 15. The design of the cam surface 30 is such that after a slight inward movement of the spring arm end 4b under an impact received by the bumper, the end of the spring arm will engage the cam surface 30 for sliding movement thereon. In view of the resistance set up by the cam surface 30 to the progressive movement of the spring arm end 4b inwardly of the housing, the spring arm will be flexed in such a manner as to not only reinforce the main bar 1 but also to bring about the maximum shock absorption possible. A detail analytic discussion with reference to this flexure with respect to this form as well as with reference to the other forms to be described will be given hereinafter.

While this form of construction utilizes a wear plate 23, it is to be understood that the use of the same is entirely optional in this instance as well as in all the other modified forms of connection to be described hereinafter.

In the form of connection shown in Fig. 6, the housing 35 is preferably made in the form of a casting having a front wall 36, a rear wall 37, side wall 38 and end walls 39 that are spaced from the front wall 36 to provide openings 40. Integrally formed with the housing 35 is a cam block 41 provided with the cam surfaces 42, said cam surfaces merging with the inner surface of the front wall 36.

Extending within the housing 35 through the openings 40 are the end portions 4c of the spring arms 4, which slidably engage the front wall 36. To retain the spring arm end 4c in frictional engagement with the wall 36 there is provided a coil spring 45 arranged transversely within the housing 35 and normal to the spring arm end 4c. A spring seat 46 constituting a bearing element is carried by the forward end of the coil spring 45 and contacts the spring arm end 4c. The rear end of the coil spring 45 is seated within a suitable recess provided therefor in the rear wall 37 of the housing 35. In this particular form the rear wall 37 is provided with threaded openings 47 in each of which is threadedly mounted a cup shaped spring seat 48 in which the rear end of the coil spring 45 is positioned. This construction facilitates the assembly of the spring 45 within the housing and also permits an adjustment in the compression thereof. The housing 35 is secured to the main bar 1 by the center bolt 19. In view of the depth of the cup seat 48, bodily movement of the coil spring 45 with respect to the housing 35 is positively prevented.

The modified form of housing connection shown in Fig. 7 is somewhat similar to that shown in Fig. 5. In this case the housing 50 is formed as a channel shaped stamping having side walls 51, and a rear wall 52, that is curved towards the ends of the housing but terminates short thereof to form the openings 53, as clearly shown. Arranged longitudinally within the housing 50 is a cam member 55, provided with similar curved cam surfaces 56 that extend outwardly from the center portion of the rear wall 52 of the housing to the ends thereof. The end portions of said cam surfaces being substantially flat

as at 57, and constituting in effect a front wall of said housing. The central portion of the cam member 55 is preferably flattened as at 58 and is secured to the rear wall 52 of the housing in any suitable manner as by the welds 59^a. Aligned openings are respectively provided in the central portion 58 and rear wall 52 for the reception of the bolt 19 which attaches the housing 50 to the main bar 1. In order to prevent buckling 10 of the walls of the housing, the bolt 19 may be provided with a spacer sleeve 59^b. The cam member 55 is preferably made of flat spring stock of a width substantially equal to the distance between the side walls of the housing so as to snugly 15 fit therebetween, the flat portions 57 thereof being adapted to engage the rear surface of the main bar 1.

The end portion 4^d of the spring arm 4 extends through the opening 53 and slidably engages the portion 57 of the cam surface 56, and is frictionally retained in position by the laminated leaf spring 59, similar in form to the spring 24 shown in Fig. 5. The outer end of the spring 59 engages an abutment 60 formed on the rear wall 25 52 of the housing 50, the inner end thereof being normally spaced from the cam member 55 in order that endwise movements of the spring 59 be permitted. In the assembly of the spring 59 within the housing, the same is placed under 30 compression and in view of the mounting thereof, as shown, is positively retained therein.

In Fig. 8, the connection comprises a channel shaped housing 60 provided with the side walls 61 and bottom wall 62. Formed centrally on the bottom wall 62 and extending between the side walls 61 is an inwardly directed transverse boss 63 on which is seated the indented portion 64 of the cam member 65, to positively center said cam member within the housing. The cam member 40 65 is provided with similar cam surfaces 66 that extend towards the ends of the housing for engagement with the rear surface of the main bar 1 which said housing 60 is attached by the bolt 19, the nut 20 thereof being positioned within 45 the boss 63. A spacer sleeve 67 may be provided if desired in surrounding relation to the bolt 19.

Preferably the cam member 65 is made of flat heavy spring stock of a width equal to the distance between the side walls 61 so as to snugly 50 fit therein, the end portions being tapered as at 68 in order to reduce the clearance between the spring arm 4 and the rear surface of the main bar 1.

The end portion of the spring arm 4 is bowed 55 as at 4^e to provide spaced surfaces 69 and 70 adapted to slidably engage the cam surface 66 adjacent the other end thereof. The bowed portion 4^e is also adapted to have bearing engagement with a wear plate 71 provided on the bottom wall 62. In the assembly of the parts comprising this connection, the spring arm end 4^e is normally maintained in frictional engagement, both with the cam surface 66 and the wear plate 71. Movement of the bowed end 4^e inwardly will 60 be frictionally resisted by the cam surface 66 as the same causes flexure of the spring arm 4.

In the connection shown in Fig. 9, the housing 75 is of channel form, and constitutes the side walls 76, and bottom wall 77. Arranged 70 within the housing 75 is a spring leaf 78, provided with a central convex portion 79, formed between concave portions 80, the end portions 81 being bowed inwardly in opposed relation, each end portion terminating in an outwardly directed 75 abutment 82. The spring leaf 78 is preferably

formed of flat highly resilient spring stock and has formed on the convex portion 79 an opening, through which the bolt 19 projects in attaching the housing 75 to the main bar 1. Arranged between the leaf spring 78 and the main bar 1 is a 5 spacer sleeve 83 and washer 84 under which the leaf spring 78 is placed under an initial compression. A wear plate 23 mounted on the rear surface of the main bar 1 is retained in position to the bolt 19 and spacer sleeve 83. 10

Each of the spring arms 4 extend within the housing 75, the end portion 4^f being somewhat curved and adapted to slidably contact the wear plate 23. Immediately adjacent the end of the spring arm there is provided a tongue-like projection 85 preferably struck out of the body of the spring arm, see Fig. 10, which projection is adapted to extend through a suitable opening 86 provided in the spring leaf end portion 81, the end of said spring arm abutting the upstanding 20 abutment 82. To lock the ends of the spring arm and leaf spring together there is provided a cotter-pin or any other suitable fastening means 87.

The spring arm end 4^f is maintained in frictional sliding engagement with the wear plate 23 25 by the spring leaf 78, which in view of the initial compression thereon reacts through the looped portion 81 to resiliently urge the spring arm end 4^f against the wear plate 23 with a pressure sufficient to produce the desired frictional resistance. 30 Movement of the spring arm end 4^f inwardly into the housing is not only resisted by the friction set up by the leaf spring 78 but also by its resilient action as the same is deflected in view of the connection therebetween. The resistance to 35 deflection set up by the spring 78 and its effect on the spring arm 4 is the same as that produced by the cam surface in the connections hitherto described.

In all the preceding forms of connections a 40 resilient medium has been employed to urge the spring arms against a surface supported by the main bar and positioned between said spring arms and the housing enclosing the same. In the form of connection shown in Figs. 11 and 12, the 45 resilient medium is interposed between the main bar and the cam surface which is urged into frictional engagement with the spring arm sliding thereon.

The housing 90 of Fig. 11 is somewhat box 50 shaped and comprises the side walls 91, bottom wall 92 and end wall 93 provided with openings 94. Arranged within the housing 90 is a cam member 95 similar in form to the cam member 55 shown in Fig. 7, differing therefrom only in 55 that the end portions of the cam surfaces 96 are spaced from the main bar 1, said cam member 95 being preferably fastened to the central portion of the wall 92 by welds 97 or any other suitable fastening means, and provided with a bolt 60 opening 98. Fitted within the area defined by the cam member 95 and the side walls of the housing 90 is a rubber block 100, provided with a central transverse bolt opening 101. The housing 90, cam member 95 and rubber block 100 are attached to the main bar 1 by the bolt 19, the initial size of the rubber block being such that the same is placed under an initial compression. If desired additional bolts 102 may be employed 65 at the ends of the housing. 70

Extending into each of the openings 94 in the ends of the housing 90 are the spring arms 4, the end portions 4^e being adapted to slidably frictionally engage the cam surfaces 96. Preferably the spring arm end 4^e is formed with a projecting cup 75

shaped seat 103 which acts as a raceway for the roller bearings 104 seated therein adapted to have bearing engagement on the wall 92 of the housing 90. At each of the ends of the wall 92 there is provided a stop 105 to limit outward movement of the spring arm ends 4^h. The surface of the rubber block 100 adjacent the main bar 1 is formed with corrugations 106 to permit the rubber to flow as the same is additionally compressed by the movement of the spring arm end 4^h on the cam surface 96. Referring to Fig. 12, it will be noticed that the width of the cam member 95 is slightly greater than that of the spring arm end 4^h and less than the width of the housing so that in effect the cam surface 96 floats on the compressed rubber block 100. The pressure exerted by the rubber block 100 is sufficient to maintain the frictional engagement of the spring arm end 4^h on the cam surface 96 and at the same time maintain the rolling engagement of the rollers 104 on the wall 92. Thus, inward movement of the spring arm ends 4^h under impacts received by the bumper will be yieldingly resisted by the cam member 95 and rubber block 100 as well as by the frictional resistance set up by the sliding movement of the spring arm end 4^h on the cam surface 96.

Figs. 13 and 14 illustrate specific forms of connections employing rubber blocks as the resilient medium, cooperating with cam members.

In Fig. 13, the housing 110 is in the form of a box provided with opening 111 at the ends thereof. The bottom wall of the housing is formed with a central interiorly directed boss 112 extending transversely of the housing to define spaced seats 113. A cam member 114 similar to the cam member 55, Fig. 7 is provided with cam surfaces 115 and is secured to the boss 112 by the welds 116 or any other suitable fastening means, both the cam member and the boss having aligned openings 117 to permit the insertion of the bolt 19 which secures the housing 110 to the main bar 1. The cam surfaces 115 are suitably curved, the outer ends thereof being adapted to engage the rear surface of the main bar 1.

Extending through the openings 111 are the end portions 4^h of the spring arms 4, each of which is adapted to frictionally slidably engage a cam surface 115. To maintain this frictional engagement there is provided rubber blocks 118 molded in the form of a parallelogram. One end of the rubber block unit is seated in locked engagement within the seat 113 provided in the housing 110, the other end of said rubber block engaging the slidable end portion 4^h of the spring arm 4 and held in locked engagement thereby, by the abutments 119 and 120, said rubber block 118 being normally under an initial compression.

Movement of the slidable spring arm ends 4^h inwardly will deform the rubber blocks 118 in such manner as to offer a progressive increase in the pressure the same exerts on said arm ends 4^h in the production of the frictional resistance offered to the sliding movement of said arm ends 4^h on the cam surface 115. This in addition to the resistance set up as the arm ends 4^h slide over the cam surfaces 115, constitute an exceedingly efficient shock absorption medium for the impacts delivered on the bumper.

If desired the area defined by the cam member 114 and the side walls of the housing 110 may be filled by a rubber block 121 indicated by the dotted lines in Fig. 13.

In Fig. 14, the housing 123 is of box-like forma-

tion and of a size sufficient to accommodate the sliding end of one spring arm 4 which enters the housing through the opening 124, said housing being secured to the main bar or supporting member 1 by the bolts or rivets 125. Fitted within the housing 123 is a cam member 126 provided with the cam surface 127 and so arranged as to extend diagonally with the housing, one end thereof being fastened to the bottom wall of the housing as by the weld 128, said end being furthermore provided with an abutment 129. The other end of said cam member is adapted to engage the rear surface of the main bar 1 adjacent the opening 124 in the housing. The end portion 4^h of the spring arm 4 slidably engages the cam surface 127 and is frictionally retained in contact therewith by the rubber block 130, one end of which is locked to the housing 123 by the cam abutment 129 and housing shoulder 131 as clearly shown, the other end thereof abutting the spring arm end 4^h. The general form of the rubber block 130 and its operation is similar to that of the rubber block 118 shown in Fig. 13. If desired the cam member 126 which is preferably formed of flat spring stock, may be backed up by a rubber block 132, to increase the rigidity of the structure.

Another method of imposing such endwise resistance to the inward movement of the spring arms consists in the provision of a resilient means adapted to be compressed by the end of said spring arms. Such a construction is shown in Figs. 15, 16, 17 and 18.

Referring to Figs. 15 and 16 there is shown a tubular housing 135 rectangular in cross-section disposed with its front side wall 136 adjacent the main bar 1, the rear side wall 137 being provided adjacent each end thereof with a circular recess 138. Extending through the open end of the housing 135 is the end portion 4^h of the spring arm 4 adapted to slidably engage the front wall 136 of the housing, the end of the portion 4^h being formed with an abutment 139 of a width sufficient to fit between the walls 136 and 137 without binding. To maintain the frictional engagement of the end portion 4^h with the surface of the wall 136 there is provided a volute spring 140 adapted to be seated within the recess 138, the small end convolution carrying a wear button 141 adapted to abut the spring arm end 4^h.

Disposed between the opposed abutments 139 at the end of the spring arms 4 is a rubber block 142 provided with a central opening 143 and concaved depressions 144 in the side walls 145 thereof for a purpose to be hereinafter described. At each end of the rubber block 142 there is arranged a follower plate 146 adapted to be engaged by the abutment 139.

The housing 135 is attached to the main bar 1 by the center bolt 19 and if so desired, by the end bolts 147, the bolt 19 passing through the opening 143 in the rubber block 142 to lock the same within the housing. It is obvious from the above construction that sliding movement of the spring arm end 4^h is resisted in two ways. First, to the functional resistance produced by the pressure executed by the volute spring 140 and secondly by the resiliency of the rubber block 142, the depressions 144 thereof permitting compression of the rubber block to accommodate said movement. This resistance, particularly to the endwise movement of the spring arm end 4^h will produce an added flexure or deflection of the spring arm 4 to reinforce the main bar 1 as will be described in greater detail hereinafter. In 75

view of the compactness of this form of construction, and high capacity of the volute spring there is produced a highly satisfactory and efficient shock absorbing connection of comparatively little cost.

If desired there may be interposed between the spring arm end 4^j and wall 136 a wear plate such as 23 previously described.

In Fig. 17, the connection shown is similar to that of Fig. 15 except that the volute springs have been omitted. In this construction the housing 150 is of channel form the bottom wall 151 thereof being provided with inwardly curved ends 152 that terminate short of the housing ends to define an opening 153 at each end thereof. Centrally arranged within the housing 150 is a rubber block 154 identical with the rubber block 142 in Fig. 15, said block and housing being attached to the main bar 1 by the bolt 19. Positioned adjacent the rear surface of the main bar 1 between the same and the rubber block 154 is a wear plate 23 adapted to be slidably engaged by the end portion 4^k of the spring arm 4 disposed within the housing 150. The end 4^k of the spring arm 4 is provided with a reversely bent loop 155 that exerts a spring action on the wall 151 to maintain the frictional engagement of the end portion 4^k on the wear plate 23. The portion 156 of the loop 155 acts as an abutment against the follower plate 157 interposed between the rubber block 154 and said abutment.

A more elaborate form of connection is shown in Fig. 18, which comprises the substantially channel shaped housing 160, having side walls 161 and a bottom wall 162. The end portion of the spring arm 4 disposed within the housing, in this case comprises a spring eye 4^m that is preferably maintained as a closed cylinder by the weld 163. Fitted within the eye 4^m is a bearing sleeve 164 adapted to have rotatably mounted therein an eccentric 165 which in turn is rotatably mounted on the bolt or pin 166 rigidly supported in any suitable manner, not shown by the side walls 161 of the housing 160.

Supported within the housing 160 is a rubber block 167, provided with the central opening 168 through which the bolt 19 extends to attach the same and the housing 160 to the main bar 1, said block extending between the opposed spring arm eyes 4^m. Arranged between the eye 4^m and the ends of the rubber block 167 is a combined wear and follower member 168, one end 169 of which slidably engages the bottom wall 162 of the housing. The follower 168 encircles that portion of the eye 4^m immediately adjacent the rubber block 167, extending rearwardly of the eye as at 170 with the other end terminating at the opening in the housing as clearly shown. The wear portion 170 of the follower is spaced from the main bar 1, there being interposed therebetween a rubber strip 171, preferably integral with the main body of the rubber block 167. The rubber strip 171 may be additionally provided with a bearing cap 172.

The normal relationship of the parts is as shown in Fig. 18, the initial compression of the rubber block 167 being such as to maintain the eccentric 165 and spring arm eye 4^m in the position shown. It is intended that the arc of movement of the eccentric be through the angle X, during which movement the spring arm eye 4^m and follower 168 will move inwardly to compress the rubber block 167. During this movement considerable frictional resistance will be set up between the spring arm eye 4^m and the follower

168, as the eye 4^m is rotated to accommodate the deflection of the spring arm 4 under impacts received by the main bar 1 of the bumper. An additional frictional resistance is produced by the movement of the cap 172 on the rear surface of the main bar 1, inasmuch as the same is constrained to move simultaneously with the follower portion 170. It is thus seen that shocks received by the spring arms 4 which are deflected thereunder are effectively absorbed by the two frictional resistances as above set forth in addition to the endwise compression of the rubber block 167. This form of mounting is especially adaptable as an individual connection for a single spring arm to a suitable supporting member, such as indicated in Figs. 3 and 4.

It is to be understood that in the proper design of the construction shown in Fig. 18, the throw of the eccentric 165 should be sufficient to accommodate practically the maximum movement which the end of the spring arm 4 would have under normal deflection of the same.

In some cases it has been found that the use of the housing as a retaining member may be altogether dispensed with. In Figs. 19 to 24 there are shown typical constructions embodying this thought.

In Fig. 19 there is shown a unitary cam member 180 formed as a casting provided with similar curved cam surfaces 181 formed on the cam walls 182. The cam walls 182 branch outwardly from a central thickened bolt receiving portion 183 provided with the bolt opening 184, through which the bolt 185 extends to attach the cam member 180 to the main bar 1. The ends of the cam walls 182 are provided with leg portions 186 which are secured to the main bar 1 by the bolt 187.

Each of the cam walls 182 is formed with a centrally located longitudinally extending slot 188. Arranged for sliding movement on the cam surfaces 181 of the cam walls 182 are the ends of the spring arms 4. Inwardly of the end of each spring arm 4 there is provided an opening 189 in registry with the slot 188. A bolt 190 with its head 191 seated on the inner surface of the cam wall 182 extends through the slot 188 and opening 189. To maintain the end of the spring arm in frictional engagement with the cam wall 182, there is fitted on the bolt the spring plate 192, retained under compression by the nut 193 on the bolt 190. If desired there may be placed within the slot 188, a wear sleeve 196 turnably mounted on the bolt 190. In addition, a wear plate 197 may be interposed between the head of the bolt 190 and the inner surface of the cam wall 182.

Under impacts delivered to the main bar 1 of the bumper there will be a deflection in the spring arms 4, the ends thereof accordingly sliding over the cam surfaces 181. This sliding movement of the spring arm carrying the bolt 190 and plate spring 195 therewith, is resisted as in all the other previous cases described hereabove by a frictional resistance produced by the action of the spring plate 195 as well as the end wise resistance set up in the spring arm by its necessity in following the cam surface contour 181 as will be described in detail hereinafter.

The construction of Fig. 20 differs essentially from that of Fig. 19 in that the slot is provided in the spring arm, the bolt being rigid with the cam member. In this case the cam wall 182^a is provided with an opening 198 adjacent the outer end thereof adapted to register with the slot 199 formed in the end portion of the spring arm 4.

slidably engaging the cam surface 181^a. Extending from the spring arm inwardly of the cam member 180^a, through the slot 199 and opening 198 is the bolt 200. The head of the bolt is preferably found on its under surface with a cylindrical surface 201 on which the spring arm may have a somewhat rocking movement. To maintain the frictional engagement of the spring arm 4 on the cam wall 182^a there is provided a rubber spring 202 on the bolt 200 and seated on the inner surface of the cam wall 182^a. A plate member 203 is fitted over the rubber spring 202 which compresses the same and is thus retained by the pin 204. It is obvious that the rubber spring 202 may be replaced either by a plate spring such as 195, Fig. 19, or any other suitable spring element.

The construction shown in Figs. 21 and 22 is somewhat on the order of that disclosed in Fig. 19. 20 The cam member 210 in this case is formed with a central depressed attaching portion 211, the bottom of which is in the same plane with the legs 212 formed at the outer ends of the cam walls 213, said cam member being attached to the main bar 1 by the center bolt 214 and end bolts 215. The longitudinal slot 216 formed in the cam walls 213 is formed with outwardly tapered walls 217, most clearly shown in Fig. 22. As in Fig. 19 the spring arm 4 is provided adjacent its end with an opening 218 in registry with the slot 216. A bolt 219 provided with a wedge shaped head 220 having tapered sides adapted to cooperate with the tapered sides 217 of the slot 216, extends through said slot and opening 218, and is provided 35 with a plate spring 221 held under compression by the nut 222.

The mode of operation and results obtained in their form of construction is identical with the form shown in Figs. 19 and 20. The cooperating tapered sides in the bolt head 220 and sides 217 of the slot 216 produce an automatic wear take up means to compensate for any wear taking place in the slotted connection. This construction furthermore acts to positively prevent any rattling of said parts of the bumper.

In much the same manner, the tapered slot and bolt head construction may be adapted to the form of connection wherein the slot is provided in the spring leaf, such for example as shown in Fig. 20.

In Figs. 23 and 24 the connection comprises a cam member 230 similar in structure to the cam member 210, in Fig. 21, and is attached to the main bar 1 by the centre bolt 231 and end bolts 232. Each of the cam walls 233 have formed thereon the longitudinal slots 234. The spring arm 4 is provided adjacent its end with spaced rectangular openings 236 and 237 of a width equal to the width of the slot 238 and arranged to register therewith, the end portion of said spring arm slidably engaging the cam surface 235.

Fitted within the slot 234 is a bearing clip 238 provided with spaced arms 239 of a width adapted to snugly fit within the openings 236 and 237 in the spring arm 4 and of a length to project for a distance therebeyond, for a purpose to be herein-after described. The top or bight portion of the clip is formed with laterally extending bearing supports 240 having the shoulders 241 formed at each end thereon all as most clearly shown in Fig. 24. Disposed between the inner surface of the cam wall 233 and the bearing supports 240 of the clip 238 are a plurality of anti-friction roller bearings 242 which are retained in position by 75 the shoulders 241. To maintain the frictional en-

gagement between the spring arm 4 and the cam surface 235 there is positioned between the arms 239 of the clip a rubber spring 245 that is retained under an initially high compression by the retained cap 246 supported on the arms 239 and locked thereto by the locking pin 247 or any other suitable means. If desired the rubber spring 245 may be replaced by any other type of suitable spring such as volute, helical or conical coil, or plate spring means. To support the arms 239 as well as the center portions of the roller bearings there is positioned in the slot 234 between said arms the block 248, which may be of lubricant impregnated wood or metal.

In this form of connection it will be appreciated that the friction producing pressure set up by the rubber spring 245 is distributed over a wide area, the frictional resistance to the sliding of the spring arm 4 being restricted to the engaging surfaces of said spring arm and cam surface, in view of the roller bearing support of the clip 238 on the inner surface of the cam wall 233. In addition all rattling of parts is positively prevented.

In each of the forms shown in Figs. 19, 20, 21 and 23 the cam walls are shown of substantial thickness and rigidity and possess the additional function of a wear plate.

The function and operation of the shock absorbing connection as embodied in the various forms above described will now be set forth with reference to the diagrammatic showing in Figs. 25, 26 and 27.

In Fig. 25 there is diagrammatically shown one half of a bumper showing a main bar 1, a spring arm 4 comprising parts of the back bar 2 which is connected at one end to the main bar as at 3. The back bar being supported by the vehicle frame 7. The free end of the spring arm 4 slidably engages a surface S on the main bar 1 and is disposed within the housing 5 carried thereby. Within the housing and adjacent the spring arm end is the cam member provided with the cam surface C. A resilient means R maintains the spring arm 4 in frictional engagement with the surface S. In the assembled bumper the normal relationship of the parts thereof is as shown in Fig. 25. When the main bar 1 is acted upon by the force of an impact designated F_i the back bar 2 and spring arm 4 will be deflected as shown in Fig. 26, the free end of the spring arm 4 slidably moving on the surface S and on the cam surface C, the force acting within the bumper being that of the resilient means indicated F_r producing the force dynamic frictional resistance indicated F_{f/r} and that acting against the end of the spring arm set up by the cam surface C and indicated F_c. In view of the deflection of the spring arm 4 as a result of the impact F_i in conjunction with the further deflection thereof produced as the end thereof is forced over the cam surface C, the additional forces indicated by the small arrows F_d are produced, which incidently increase by a substantial amount the force F_{f/r} of frictional resistance.

It will be noted that as the end of the spring arm 4 is forced over the cam surface C that the spring arm 4 is so deflected thereby as to back up or flatten out along a substantial surface of the main bar 1, which as indicated by the forces F_d act to reinforce the main bar 1 to the shocks of impact. The shock delivered by the force of impact F_i is thus effectively absorbed by the forces F_{f/r} and F_c acting in opposition to the sliding movement of the spring arm 4 as well

as by the forces F_D which act in opposition to the force F_r that also reinforces the main bar 1. It is apparent that the greater the deflection of the spring arm 4 the greater the forces F_c , F_d and F_{fr} will become.

In Fig. 27 there is shown diagrammatically the form of connection wherein the cam member C is replaced with a resilient means R', acting to resiliently oppose endwise movement of the spring arm 4. The force F_c , Fig. 26, is accordingly replaced by the force F_{fr}' , acting on the abutment formed on the end of the spring arm 4. The yielding resistance F_c to the inward movement of the spring arm 4 will produce the same flattening out effect on the spring arm 4 as described above, the connection thus functioning and operating in the same manner as that of Fig. 25.

The invention and manner of operation of the same having been described as above set forth, what I claim is:—

1. In a bumper provided with a spring arm member having an end portion movably engaging a supporting element, and means carried by said supporting element and adapted to be engaged by the terminal end of said spring arm end portion, said supporting element having a portion of same for imposing an increasing progressive resistance to the endwise movement thereof in one direction of movement of the arm.

2. In a bumper provided with a spring arm member having an end portion slidably engaging a supporting element, means carried by said supporting element for producing a frictional resistance to said sliding movement and including means disposed in the path of movement of said end portion for imposing a resistance to the endwise movement thereof in one direction.

3. In a bumper provided with a spring arm member having an end portion slidable relative to a supporting element, resilient means associated with said spring arm for producing a frictional resistance to said sliding movement and additional means carried by said supporting element for imposing a resistance to the endwise movement of said spring arm in one direction.

4. In a bumper comprising a supporting and a supported member, a spring arm carried by one of said members for sliding movement relative to a surface of the other, means associated with said spring arm for producing a frictional resistance to said sliding movement and including sequentially operative means for resisting endwise movement thereof in one direction.

5. In a bumper, a pair of opposed spring elements adapted for sliding movement on a surface of a supporting member, resilient means associated with each of said spring elements for producing a frictional resistance to said sliding movement and means operative between said spring elements for resisting endwise movement thereof towards each other.

6. In a bumper comprising a supported member and a supporting member, a spring arm carried by one of said members having upon deflection of the same an end thereof adapted for movement relative to the other of said members, and means carried by said last mentioned member arranged in the path of movement of said spring arm end for additionally deflecting the same to impose a resistance to said endwise movement.

7. In a bumper comprising a supported member and a supporting member, a spring arm carried by one of said members having upon deflection of the same an end thereof adapted for move-

ment relative to the other of said members, and abutment means carried by said last mentioned member arranged in the path of movement of said spring arm end for additionally deflecting the same to impose a progressively increasing resistance to said endwise movement.

8. In a bumper comprising a supported member and a supporting member, a spring arm carried by one of said members having upon deflection of the same an end thereof adapted for sliding movement relative to the other of said members, means providing a cam surface carried by said last mentioned member and arranged in the path of movement of said spring arm end for deflecting said end away from said last mentioned member whereby there is imposed a progressively increasing resistance to said endwise movement.

9. The structure specified in claim 8, and resilient means associated with said spring arm end for producing a frictional resistance to the sliding movement of the same.

10. In a connection between two elements of a bumper at least one of which is resilient and formed with an end portion having slidable movement relative to the other comprising a supporting member carried by the other of said elements having a surface normally engaged by said end portion, spring means mounted on said supporting member and associated with said end portion for producing a frictional resistance to the initial sliding movement thereof on said surface and sequentially operative means arranged in the path of movement of said end portion for imposing an additional resistance to the endwise movement thereof.

11. In a bumper provided with a spring arm member having an end portion slidably engaging a supporting element, resilient means associated with said end portion for producing an initial frictional resistance to said slidable movement and a cam surface so constructed and arranged as to be slidably engaged by the end of said spring arm after a predetermined movement thereof to impose an additional resistance to said slidable movement.

12. In a bumper provided with a spring arm having an end portion thereof slidably movable on a supporting element upon deflection of said spring arm, a cam member carried by said supporting element and provided with a cam surface so constructed and arranged as to be slidably engaged by the end of said spring arm end portion whereby a resistance to said movement will be imposed thereon as to additionally deflect said spring arm to provide a progressive engagement of said spring arm with said supporting element.

13. The structure specified in claim 12, and resilient means associated with said spring arm end portion for producing an initial frictional resistance to the sliding movement thereof.

14. In a bumper comprising a main bar a back bar, a spring arm carried by said back bar and under deflection thereof adapted to have an end portion slidably movable relative to said main bar, means connecting said spring arm end portion to said main bar comprising a cam member secured to said main bar and provided with a surface, a portion thereof being disposed substantially parallel to said main bar and normally engaged by said spring arm end, the remaining portion of said surface being curved away from said main bar to define a cam surface adapted to be engaged by said spring arm end upon movement thereof whereby there is produced a resist-

ance to the endwise movement of said spring arm end to cause an additional deflection of said spring arm.

15. In a bumper comprising a supporting member and a supported member, a spring arm element carried by one of said members and having an end thereof adapted for slidable movement relative to said other of said members, a cam element carried by said last mentioned member provided with a surface adapted to be engaged by the end of said spring arm element, a longitudinal slot in one of said elements, a connecting means carried by the other of said elements arranged for sliding movement in said slot, and resilient means carried by said connecting means for maintaining said elements in frictional engagement, the portion of said surface adjacent the end of said spring arm element in the normal position thereof defining a cam surface of such a curvature as to impose a resistance to the endwise movement of the end of said spring arm element.

16. In a connection between two elements of a bumper at least one of which is resilient and formed with an end portion having slidable movement relative to the other comprising a member carried by the other of said elements provided with a surface normally engaged by the end portion of said resilient element and including a cam surface adjacent said end portion arranged in the path of movement of the same to impose a resistance to the endwise movement thereof, and cooperating guide means positively connecting said end portion to said member including spring means for maintaining the same in frictional engagement with said surfaces and to produce a frictional resistance to the movement thereon.

17. In a connection between two elements of a bumper at least one of which is resilient and formed with an end portion having slidable movement relative to the other comprising a member carried by said other element provided with a surface normally engaged by said end portion, resilient means mounted on said member and arranged in the path of movement of said end portion to resiliently resist said movement, said end portion having associated therewith spring means to maintain the same in frictional engagement with said surface.

18. In a connection between two elements of a bumper at least one of which is resilient and formed with an end portion having slidable movement relative to the other comprising a member carried by said other element provided with a surface normally engaged by the end portion of said resilient element and an additional cam surface adjacent said end portion arranged in the path of movement of the same

to impose a resistance to the endwise movement thereof, said end portion having associated therewith spring means to maintain the same in frictional engagement with said surfaces.

19. In a connection between two elements of a bumper at least one of which is resilient and formed with an end portion having slidable movement relative to the other comprising a housing member carried by said other element having therein a surface normally engaged by said end portion, a cam surface supported within said housing member and arranged in the path of movement of said end portion to impose a resistance to the endwise movement thereof and spring means mounted within said housing member and associated with said end portion to maintain the same in frictional engagement with said surfaces.

20. In a connection between a main bar of a bumper and a pair of spring arms having opposed end portions arranged for sliding movement relative to said main bar and towards each other comprising a housing member carried by said main bar having therein a surface normally engaged by each of said end portions, a cam member supported within said housing having a pair of cam surfaces each arranged in the path of movement of an adjacent end portion to impose a resistance to the endwise movement thereof and spring means mounted within said housing for association with each of said end portions to maintain the same in frictional engagement with said surfaces and to produce a frictional resistance to the movement thereon.

21. In a bumper, a main bar, a back bar comprising a pair of spring arms, each spring arm being connected at least at one end to the main bar, housing means secured to the main bar, the other ends of said spring arms being each adapted to extend within said housing means for slidable frictional movement therein, resilient means within the said housing for producing said frictional resistance to said sliding movement and additional means operative in the path of movement of the ends of said spring arms for resisting endwise movement thereof.

22. In a bumper provided with a main bar, a back bar comprising a pair of spring arms, each spring arm being connected at one end to the main bar, the other ends of said spring arms being arranged in opposed relation for sliding engagement with a surface on said main bar, resilient means associated with each of said opposed ends for producing a frictional resistance to said sliding movement and means operative in the path of movement of said opposed ends for resisting endwise movement thereof.

VILLOR P. WILLIAMS.
